Primary Examiner — Cynthia Ramirez*(74) Attorney, Agent, or Firm* — Stiennon & Stiennon(57) **CLAIM**

The ornamental design for a waste collecting container, as shown and described.

DESCRIPTION

FIG. 1 is top perspective view of the waste collecting container of our invention;

FIG. 2 is a bottom perspective view thereof;

FIG. 3 is a left side elevational view thereof, the right side elevational view is identical thereto;

FIG. 4 is a front elevational view thereof, the rear elevational view is identical thereto;

FIG. 5 is a top plan view thereof; and,

FIG. 6 is a bottom plan view thereof.
